FEED TABLE

Georg Spiese, Leipzig, Germany

Application April 25, 1938, Serial No. 294,231
In Germany April 30, 1937

2 Claims. (CL. 271—52)

This invention relates to a feed table of the inclined roller type which is provided with an adjustable guide rail for adjusting and feeding sheets to a machine and which may be particularly used as cross feed table between two sheet folding devices, etc. arranged at an angle to one another, in which the sheet is pressed against feed rollers acting on the underside of the sheet by means of pressure rolls or the like.

When tables of this kind are employed, particularly as cross feed tables in folding machines, slipping of the sheets relative to the feeding means cannot be avoided if the pressure members acting from above are rotated solely by the sheet friction. When the sheets are placed on the table rectangularly to the guide rail determining the direction of feeding, conveying will temporarily stop, since the sheets in order to be able to pass under the pressure means must lift them off from their driving rolls and check the rotation thereof. The sheets have to be started by the friction of the lower rolls and then increase the speed of the pressure members by the friction developing between the latter and the sheets. In cross folders it is of essential importance for the output of the machine that cross folding is effected without any stop and a sheet is fed already in the new direction when the following one coming from the preceding folding mechanism reaches the guide rail. When several sheets simultaneously and side by side arrive at the cross feed table, accurate forwarding without slipping is highly important. It is known to connect the upper pressure rolls in cross feed tables with the lower feed rollers by a toothed gearing so as to drive the upper and lower rolls simultaneously at uniform speed, but this positive connection is relatively expensive and clumsy and interferes with the easy mobility of the pressure means, which is required to permit a cross fed sheet to pass under the pressure rolls without delay. Exchange and adjustment of the pressure roll along the guide rail are not possible in known cross feed tables, and if a toothed wheel happens to drop out, the entire roller drive will be stopped.

The invention avoids the drawbacks connected with the known type of cross feed tables and by providing for driving of the pressure rolls by the feed rollers independently of the sheet drive insures easy yielding of the pressure rolls and adaptability to the requirements of operation and the changing nature of the material to be worked.

The invention consists in providing that the

pressure means, as rolls, brush wheels, etc., adjustable along the guide rail, are separately connected with their respective feed rollers by a selectively engageable and disengageable gear arranged on the other side of the guide rail. 5 Each pressure member is driven by its feed roller through the medium of a frictional gearing formed of the feed roller and a friction wheel disposed on the shaft of the pressure member, the frictional pressure of the wheel being regulatable like the pressure of the upper roll of the brush wheel upon the lower conveying roller. The bearing of the friction wheel and pressure member may further be arranged in with respect to the pressure member known elastically yielding manner with adjustable spacing from the feed roller. To permit adjustment of the friction wheel and pressure member independently of one another each possesses a special axle connected by known means, as a flexible shaft, 10 etc., which render independent adjustment possible. In this way, the mobility and adaptability of the pressure member are insured without reacting on the frictional gearing. The friction wheel can be readily removed and exchanged to 15 permit at will one or the other kind of sheet drive, with or without driving the pressure member. This arrangement, furthermore, makes it possible to use friction wheels of different diameters to vary and regulate at will the circumferential speed of the pressure member relative 20 to that of the lower rolls, i. e., the feeding speed of the sheets can be reduced by attaching friction wheels of larger diameter and increased by employing friction wheels of smaller diameter. 25 The friction wheels are preferably provided with an exchangeable frictional covering, as a rubber ring, etc.

By way of example, one form of the invention is illustrated in the accompanying drawings, in 40 which all parts not required for understanding the invention have been omitted.

Figures 1 and 2 are, respectively, a view and a plan of the general arrangement of a cross feed table of a buckling folder for cross folding. 45

Figs. 3 and 4 are, respectively, a view and a plan on an enlarged scale of the driving connection between the driving feed roller and the driven pressure member.

Fig. 5 is a section of the bearing body of the 50 pressure member on the line A—B, of Fig. 4.

Fig. 6 is a view of the bearing body of a pressure member seen in the direction of the arrow C in Fig. 5, and

Figs. 7 and 8 are enlarged partial sections, 55

corresponding to Fig. 5, which show the adjustable bearing of the shafts of the friction or brush wheels.

The sheets pass over a feed table 1 of inclined roller type into the first folding mechanism 2 connecting with parallel folders. The sheets coming out of the last parallel folder 3 are cut in travelling direction by a longitudinal cutter comprising two circular knives 4, 5, and the cut sheet portions pass over a guide plate 6 between a feed roller 7 and pressure rolls 8 which place the sheets on the cross feed table. The cross feed table comprises a frame 9, feed rollers 10 obliquely arranged in the frame 9 and uniformly driven in the same direction in known manner, a directing and guide rail 11 adjustable in the lateral direction of the table, and pressure members in the form of brush wheels 12 adjustably disposed on the rail 11 and parallel arranged with their axes to the feed rollers 10. The casing-like bearing bodies 13 of the brush wheels 12 are longitudinally displaceably mounted on the guide rail 11 of the cross feed table by means of a foot 14 and can be held in position by a clamping screw 15. The bearing 16 of the shaft 17 of the brush wheels 12 possesses a set screw 18 which passes through a bore of the body 13 and is provided on the outside with an adjusting nut 19. Between the bearing 16 and a shoulder of the bore of the casing a spring 20 is fixed. The shaft 17 is further in driving connection with the shaft 22 of a friction wheel 23 through a flexible shaft in the form of a spring 21. The bearing 24 of the shaft 22 for the friction wheel 23 is provided with a screw shank 25 which passes through a bore of the casing 13 and is outside fitted with an adjusting nut 26 which is included between the casing 13 and an angular member 27 slipped over the shank 25 and secured to the casing 13 by a screw. A check nut 28 secures the adjustment of the friction disc. Instead of this arrangement for adjusting the pressure of the friction disc another arrangement similar to the one described in connection with the brush wheel may be employed.

When the casing 13 is secured to the stop rail 11, the shaft 19 of the brush wheel 12 and the shaft 22 of the friction wheel 23 unidirectionally rotate with the feed roller 10 with which the brush wheel and the friction wheel are to cooperate, the brush wheel 12 being disposed on the inside and the friction wheel 23 on the outside of the guide rail 11. The brush wheel is adjusted as to its distance from the feed roller 10 according to the nature and thickness of the material to be folded, and pressure between the friction wheel 23 and the feed roller 10 is regulated so that slipping cannot occur.

When a sheet is conveyed in the direction of the arrow D in Fig. 4 toward the guide 11, it will lift the brush wheels 12 from the rollers 10 without causing any reduction in the speed of rotation of the brush wheels which instantly engage the sheet at the speed of the roller 10. The ne-

cessary, yet as much as possible restricted, slipping of the sheets relative to the conveying means is insured by the yielding arrangement of the brush wheels, apart from the elasticity of the brushes. Owing to the combined action of the rollers 10 and brush wheels 12 the sheets are moved in the new feeding direction with the greatest possible acceleration.

By reducing frictional pressure between the friction wheel 23 and the feed roller 10 feeding drive can be reduced until it ceases completely. Furthermore, by employing friction wheels having a greater or smaller diameter than the associated feed roller the feeding drive of the brush wheels can be increased or decreased.

Any variation in the circumferential speed of a brush wheel relative to its feed roller 10, due to wear of a brush or friction wheel, can be readily compensated by exchange of a brush or friction wheel or by altering the rubbing covering of the friction wheel.

If for any reason the circumferential speed of the brush wheel relative to that of the feed roller 10 is to be reduced or increased at any point of the feed table, for instance to accelerate the speed of the sheet shortly before the folding mechanism and to retard it at a larger distance from the cross folder, both objects can be attained by simply arranging a smaller or larger friction wheel.

I claim:

1. A feed table for transferring sheets from a folding mechanism to a cross folder and including a guide rail, a series of feed rollers inclined to said guide rail and over which the fed sheets are translated, a series of pressure inducing means each associated with a respective feed roller and each having a shaft, gearing means connecting the respective feed rollers and pressure inducing means, said gearing means including a shaft supported friction wheel removably mounted on the respective shaft, and means for regulating the pressure between said friction wheel and feed roller.

2. A feed table for transferring sheets from a folding mechanism to a cross folder and including a guide rail, a series of feed rollers inclined to said guide rail and over which the fed sheets are translated, a series of pressure inducing means each associated with a respective feed roller and each having a shaft, gearing means connecting the respective feed rollers and pressure inducing means, said gearing means including a shaft supported friction wheel removably mounted on the respective shaft, means for regulating the pressure between said friction wheel and feed roller, said shafts being mounted in independently adjustable bearings, and a flexible shaft connecting said shafts whereby to permit independent adjustment of the shafts of the pressure means and friction wheel with respect to the feed rollers.

GEORG SPIESS.
